UNITED STATES PATENT OFFICE.

THOMAS F. McGUIRE, OF NEW YORK, N. Y., ASSIGNOR, BY DIRECT AND MESNE ASSIGNMENTS, TO INTERNATIONAL ACCESSORIES MANUFACTURING COMPANY, OF WILMINGTON, DELAWARE, A CORPORATION OF DELAWARE.

CARBURETER.

1,101,869.

Specification of Letters Patent. Patented June 30, 1914.

Application filed February 14, 1912. Serial No. 677,491.

To all whom it may concern:

Be it known that I, THOMAS F. McGUIRE, a citizen of the United States, and residing in the borough of Manhattan, city, county, and State of New York, have invented certain new and useful Improvements in Carbureters for Hydrocarbon-Engines, of which the following is a full and clear specification, illustrated in the accompanying drawings, the novel features of my invention being more fully pointed out in the annexed claims.

My invention relates in general to carbureters for mixing liquid fuel with air to produce a combustible mixture for use in hydrocarbon engines.

In particular my invention relates to the type of carbureters in which with the increased admission of mixture to the engine the air supply and fuel supply is increased in such proportion that the mixture admitted to the engine always is made of such quality as the engine requires at the particular speed and power intended by such increased admission of mixture.

In particular my invention relates also to the form of carbureters illustrated in a pending application of Elmer S. Smith for carbureters, Serial No. 626,678, filed May 12th, 1911, my invention being an improvement on the form illustrated therein.

The object of my improvement is to make the fuel supply through the jets, which are mounted on the rotatable gasoline container, dependent on the operation of the engine, that is to say to cause the jets to yield fuel only when the engine is running, contrary to the arrangement in the aforesaid application where the jets yield the fuel so long as they are submerged below the gasoline level in the container. By my improved construction I am also enabled to bring for any given angular position of the rotatable gasoline container any desired number of nozzles into action and if the engine should require it to bring on further angularly moving the container, a smaller number of jets into action.

In the accompanying drawings, Figure 1 is a side elevation of my improved carbureter; Fig. 2 is a longitudinal vertical section through the outer shell of the carbureter on the line 2-2 in Fig. 1; Fig. 3 is a similar longitudinal vertical section through

the gasoline container within the shell as shown in Fig. 2, the container being shown in larger scale; Fig. 4 is a plan view of the lower bowl of the container; Fig. 5 is a bottom view of the upper half of the container shown in Fig. 3; Fig. 6 is a longitudinal vertical section through the lower bowl on the line 6-6 in Fig. 4; Fig. 7 is an inside view of the two opened semi-spherical shells of the carbureter which are shown closed in Figs. 1 and 2; Fig. 8 is a section through a modification of the lower bowl similar to the section shown in Fig. 6; Fig. 9 is a vertical section at right angles and on the line 9-9 to the section shown in Fig. 8; Fig. 10 is a further modification of the bowl shown in Fig. 6.

The general form of the carbureter as shown in Figs. 1, 2 and 7 comprises substantially semi-spherical shells 1 and 2, which are hinged at one side together as shown at 3 in Fig. 2 and locked together at 4 in Figs. 1 and 2. The upper shell which is more closely semi-spherical than the lower shell is provided at its upper portion with a mixture outlet 5, whereas the lower shell 2 is formed by a cylindrical rim 6, which is hinged and locked to the upper shell as previously described and which has attached to its open end a basket 7 preferably of wire gauze, these two elements, the rim 6 and the basket 7 forming the air inlet of the shell. The upper and lower shells are provided at their abutting surfaces with diametrically oppositely arranged trunnion bearings, each of the shells having one half of the bearing integral with it which, when the shells are assembled, registers with the corresponding half of the other shell. In Fig. 1 the trunnion bearings integral with the lower shell 2 are shown at 8 and those integral with the upper shell 1 are shown at 9 and 10. In these bearings is journaled the fuel receptacle 11, by means of trunnions 12 and 13, trunnion 12 being located in bearing 8, 10 and being provided with a transverse slot 14 in which a lever 15 is suitably fastened, the upper half 10 of the trunnion bearing being cut out as shown at 16 in Fig. 7 to permit arm 15 to pass to the outside. The cut out 16 has sufficient angular extension in the wall of the bearing to permit lever 15 to

rock through a certain angle and it thereby serves simultaneously as a limiting stop which determines the angle through which the receptacle can be tilted in either direction from the normal position.

The fuel receptacle 11 is of the following construction: As will be noted from Fig. 3 it consists of two halves joined in a horizontal plane, the lower half 17 being a substantially perfect semi-sphere, whereas the upper half 18 is cone shaped with a flat top and a recess 19 in the top. The two halves are joined together by means of a screw bolt 20, which rests with its shoulder 21 in recess 19 of the upper half of the receptacle and which is threaded at its lower end into a central boss 22, provided at the lower portion of bowl 17. The upper portion of screw bolt 20 extends a suitable distance beyond shoulder 21 and serves as a guide for the mixture valve 23, which is seated against the mixture outlet of the upper outer shell 1 of the carburetor as shown in Fig. 2. This valve is yieldingly held on its seat by means of a spring 24 seated in recess 19 of the upper portion 18 of the receptacle and furthermore prevented from rotating on bolt 20 by a pin 25 fastened in the receptacle top and engaging in a corresponding recess 26, provided 30 in the under side of the valve. There is also a radially extending cam 27 provided on the upper side of the valve which when the receptacle is tilted to the right (Fig. 2) bears against the valve seat and depresses the valve so as to further increase the opening through which the mixture passes when the receptacle is tilted at a certain angle. These features are described and claimed in detail in the aforesaid application Serial No. 40 626,678, and are merely mentioned and illustrated in my application to show the complete carburetor to which my improvement refers.

Inside of the fuel receptacle is located a float 30 which is attached to float arm 31, shown in Fig. 5, which arm in turn is pivoted at 33 in a suitable support 32, located in the hollow trunnion 13. As will be noted from the plan view of trunnion 13 shown in Fig. 7 the other end of arm 31 extends close to the outer end of trunnion 13 where it registers with a transverse slot 34 provided in the trunnion wall, and the end of arm 31 is provided with a cam 35. This cam 50 operates with the lower end 38 of a gasoline check valve 41 of the usual type employed in carburetors so that when the fuel level in the receptacle falls below a certain limit and the float with it, cam 35 rises and thereby lifts 55 check valve which is located in valve casing 36, Fig. 1, to admit fuel. Valve casing 36 is seated in a boss 37 provided on the upper shell 1 as shown in Fig. 1 and the valve stem 38, as shown in Fig. 7, extends through an 60 opening 39 in trunnion bearing wall 9. This

trunnion is likewise clearly indicated in the above named application and only shown in dotted lines in present Fig. 1.

The upper half 18 of the fuel receptacle is provided adjacent to the plane at which it joins the lower half with a rim 45 which is of sufficient diameter to fit with its upper edge into a corresponding rim 46, provided in upper shell 1 as will be clearly seen from Fig. 2. Adjacent to this rim are provided a suitable number of fuel nozzles 47 which are suitably fastened in the receptacle, for instance, by threading as shown and which are provided with a small boring, which leads to the inside of the receptacle. The 70 nozzles 47 are distributed over a certain zone adjacent to rim 45, the center of the zone being located substantially in the central vertical plane through the receptacle at right angles to the trunnion axis, on which the section through the receptacle shown in Fig. 3 is taken. As will be noted from Figs. 3 and 7 this zone extends on either side of said plane circumferentially a suitable distance toward the trunnions and also 75 as shown particularly in Figs. 2 and 3 to a certain height above the fuel level $f-f$ shown in dotted lines in Fig. 3.

In the structure of the fuel receptacle illustrated in the aforesaid application the 95 nozzles 47 communicate directly with the interior of the receptacle such as is, for instance, indicated in present Fig. 3 with respect to the fuel nozzle 47^a. Thus when the receptacle is tilted or rotated clockwise in Fig. 3 the fuel nozzles gradually dip below the gasoline level $f-f$ and thus are adapted to come into operation. In the present construction the bulk of the nozzles contained in the entire zone does not directly communicate with the interior of the receptacle but they are all threaded into a boss 48, which extends inside of the wall substantially over the entire zone of nozzles as shown in Figs. 3 and 5. This boss is flush 100 with the surface of the upper half 18 of the receptacle at which it joins the lower bowl 17, as will be also noted from these figures, and the boss is provided with a number of borings 49 (Figs. 3 and 5) which correspond with the number of nozzles which are threaded into the boss and which extend upwardly into the boss a sufficient distance to meet the lateral borings into which the nozzles are threaded. One of these nozzles 110 with its boring is shown in Fig. 3 in longitudinal vertical section. In the lower bowl 17 are suitably disposed tubes 50, which are clearly illustrated in Figs. 3, 4 and 6, and which are suitably fastened to the inner 115 wall of bowl 17, such as, for instance, by clamps 51. These tubes extend at the right hand ends (Fig. 3) slightly above the plane at which the upper and lower halves of the receptacle meet and the tubes at these ends 120

125

130

are slightly tapered to fit into correspondingly tapered mouths of borings 49 so that when the two receptacle halves are drawn together by bolt 20 each tube 50 will be 5 thrust into the mouth of its boring 49 with which it is in alinement and thus connect the nozzle communicating with this particular boring with the particular tube. The left hand ends of tubes 50 extend to the 10 opposite side of the pivotal axis of the receptacle, preferably as indicated in Figs. 3, 4 and 6 along the inner wall of the lower bowl and upward, whereby these tubes terminate near the rim of the lower bowl at 15 varying distances below the gasoline level $f-f$ when the receptacle is in normal position as shown in Fig. 3. For instance it will be noted from Figs. 3 and 6 that the end 50^a of the innermost tube which is connected to the nozzle 47 located at the lowest point of the zone, as shown in Fig. 3, extends within a very short distance from the fuel level $f-f$ when the receptacle is in normal position, shown in Fig. 3, whereas the 20 free ends of the remaining tubes 50 terminate at graduated increasing distances below the fuel level $f-f$. However, in the 25 position of the receptacle shown in Fig. 3 each of the tubes terminates below the fuel level. From Fig. 3 it will be also noted that the nozzle communicating with the tube 50^a stands thus nearest to the gasoline level of all the nozzles which the zone contains which distance may be, for instance, 30 sufficient for the air drawn past the nozzles when the engine is started to draw the fuel out of this nozzle by suction and thus enrich the air with fuel to a sufficient extent to produce mixture necessary to run the engine at a certain speed. All the remaining 35 nozzles, though the free ends of their tubes are all located below the gasoline level, are as yet elevated too far above the gasoline level to discharge the fuel therethrough by 40 suction. They will only come successively into operation as the receptacle is tilted clockwise (Fig. 3) whereby, for instance, the nozzle 47 located adjacent and above the lowermost nozzle previously referred to 45 is lowered sufficiently to cause the fuel level to rise therein and come within the proper distance of the mouth of the nozzle to permit fuel discharge by suction.

The free end of each tube is located with 50 respect to the vertical position of its nozzle so that when its nozzle comes into, what shall be termed hereinafter operative position through the rotation of the receptacle, the free end still remains below the fuel 55 level. However, as soon as the receptacle is further rotated so that a certain nozzle which has previously been in operative position where fuel is discharged only by suction, is brought into a position where fuel 60 also might be discharged through its nozzle

merely on account of its mouth being located below the fuel level, the free end of its tube is elevated in this position above the fuel level and thus the nozzle is disconnected thereby from the fuel contained in the receptacle and any discharge by gravity prevented thereby, aside from the negligible small quantity of fuel which might be contained in the uppermost portion of the free end of the tube. Thus the nozzles are 70 thrown progressively into and out of operation as the receptacle is tilted more and more in the same direction, or also righted in the other direction. This action just described clearly appears from the illustration shown 75 in Fig. 3 where the free tube end 50^a is slightly below the fuel level so that its nozzle 47 is just in the position as pointed out before in which it discharges the desired quantity of fuel by suction, whereas when the receptacle is only slightly tilted this end rises 80 above the fuel level and cuts off its nozzle from further fuel supply. Since the fuel supply should of course increase as the receptacle is tilted to enrich a larger quantity of air in accordance with the increased power desired, instead of one nozzle I may place several nozzles in horizontal alinement with each other which may either come 85 into operation simultaneously if the free 90 ends of their tubes terminate at the same level or the tube of one of two nozzles which are in horizontal alinement such as, for instance, nozzles 47^b and 47^c may be slightly elevated at its free end above the other tube 95 end. For instance the two nozzles 47^c and 47^b, Fig. 7, which are approximately in horizontal alinement and only slightly offset vertically have their respective tube ends 100 50^b and 50^c at different levels as will be clearly seen from Fig. 6. By this arrangement I gain the advantage that when the angle of rotation of the receptacle is gradually increased nozzle 47^b gradually goes out of operation, whereas nozzle 47^c gradually 105 coming into operation remains operative after the first nozzle has ceased to operate. In this preferred form the relative positions of the nozzles and their free tube ends may be 110 easily adjusted so that with respect to their operative periods successive nozzles overlap each other part way, whereby at any time the fuel discharge from the receptacle is taken up by successive nozzles without interruption and may be increased with the 115 angle of rotation of the receptacle with very great exactness and corresponding with the amount of air drawn by the engine through the carbureter.

It is obvious that aside from arranging a 120 number of nozzles in horizontal alinement in order to discharge a certain amount of fuel in a certain angular position of the receptacle, the size of the opening of such nozzles may be suitably increased. Thus or 125

dinarily it is sufficient to have only two nozzles in operation at any time since I find that for the normal type of hydrocarbon engine two nozzles operating together may be provided with sufficiently large openings to supply the proper amount of fuel and still permit this amount to be sufficiently atomized by the air rushing past the nozzles.

The advantage which I gain by this construction just described over that described in the aforementioned application Serial No. 626,678 is that, should the receptacle be left in any tilted position in which any of its nozzles may be in operative position and the engine be stopped, no fuel will emanate from the nozzles since as previously described the suction of the engine is necessary to draw it therefrom, whereas otherwise my structure has the same advantages which are afforded by the construction shown in the aforesaid application with regard to the gradual increase of fuel supply with the increased angle of rotation of the receptacle.

From Figs. 3 and 5 it will be noted that there are two nozzles 47^a, which are located farthest above the fuel level in Fig. 3 and which have a direct communication with the interior of the receptacle. These nozzles are at such height that they come into operation only when the receptacle is tilted through the maximum angle which it is permitted to rotate, and should the receptacle be left in this position when the engine is stopped fuel can not emanate therefrom by gravity on account of their outer ends being still located slightly above the gasoline level when they are in operative position, so that also in this case the suction of the engine is necessary to draw the fuel therefrom. Of course also these nozzles might be slightly offset to each other in vertical direction so that first one and then the other comes into operation.

As previously explained the lowermost nozzle which connects with tube end 50^a shown in Fig. 3 is sufficient to run the engine idle at low speed with the receptacle in the position shown in Figs. 2 and 3. Sufficient air is thereby admitted to the carbureting chamber in which the nozzles are located through an opening 52 provided between rim 46 of upper shell 1 and rim 45 of the receptacle, as shown in Fig. 2, whereas these two rims meet in this position at the opposite side of the pivotal axis of the receptacle in the position which is shown in Fig. 2. Only a very small amount of mixture being necessary to turn over the engine idle, the mixture valve 23 which in this position of the receptacle is fully seated in the mixture outlet is provided with a small V-shaped notch 53, which is indicated in Figs. 3 and 7.

The form in which I have shown and described heretofore the means which connect the fuel nozzles with the fuel contained in

the receptacle is the preferred form. It is obvious that the manner in which these connections may be made is merely a matter of constructive skill and may be varied considerably within the scope of my invention. For instance, instead of using tubes 50 which run along the inner wall of bowl 17 and are attached thereto I may provide these tubes within the wall as shown at 54 in Fig. 8, where they are arranged within the integral wall 17^a of the lower bowl or they may be formed by a double wall, as shown in Fig. 10, the two portions 55 and 56 of which are provided with channels of semi-circular cross section so that two of such channels of the two walls registering will form a tube 57. The two walls may be held together in any suitable manner, for instance, by screws 58. To produce the graduated distance corresponding to the free ends 50^a and 50^b of tubes 50, previously described, I provide a boss 60 on the inside of the lower receptacle half, shown in Figs. 8 to 10, in which the several tubes 54 or 57 terminate at graduated distances from the fuel level. At the other end these tubes may be flush with the bowl rim and directly lead into borings 49 of the upper receptacle half.

Aside from the advantages as to perfect mixture gained by the above described fuel discharge device I also gain the advantage of effectively separating any impurities heavier than fuel therefrom before the fuel enters the tubes. For instance, it is obvious that water which frequently forms an undesirable admixture to gasoline will collect at the bottom of the receptacle bowl 17 where it can never reach the nozzle tubes.

What I claim is:

1. In a device of the character described, the combination with a rotatable fuel receptacle, means for maintaining the fuel therein on a predetermined level, means for discharging fuel through the wall of said receptacle when the fuel level is brought within a predetermined distance of said means by rotating said receptacle through a predetermined angle, and means for connecting said discharging means with the fuel in said receptacle and for preventing said discharging means from operating when the receptacle is rotated beyond said predetermined angle.

2. In a device of the character described, the combination with a rotatable fuel receptacle, means for maintaining the fuel therein on a predetermined level, means for discharging fuel through the wall of said receptacle when the fuel level is brought within a predetermined distance of said means by rotation of said receptacle through a predetermined angle, and means for connecting said discharging means with the fuel in said receptacle so long as the receptacle is rotated within said predetermined angle and for

disconnecting said discharging means from the fuel when the receptacle is rotated beyond said angle.

3. In a device of the character described, the combination with a rotatable fuel receptacle, means for maintaining the fuel therein at a predetermined level, and a plurality of fuel discharge means disposed in the wall of said receptacle having their outer ends normally disposed above the fuel level and their inner ends communicating with the fuel, said discharging means being adapted to come successively into operation when the receptacle is rotated from normal position, each means operating at a certain angular position of the receptacle and each of said means having the communication of its inner end with the fuel interrupted when the receptacle is rotated beyond said angular position.

4. In a device of the character described, the combination with a rotatable fuel receptacle, means for maintaining the fuel therein at a predetermined level, and a plurality of fuel discharge means disposed in the wall of said receptacle having their outer ends normally disposed above the fuel level and their inner ends communicating with the fuel, said discharging means being adapted to come successively into operation when the receptacle is rotated from normal position, each means operating at a certain angular position of the receptacle and each of said means having the communication of its inner end with the fuel interrupted when the receptacle is rotated beyond said angular position and each successive means coming into operation before the preceding means goes out of operation.

40 5. In a device of the character described, the combination with a rotatable fuel receptacle, means for maintaining the fuel therein at a predetermined level, and a plurality of fuel discharge nozzles disposed in the wall of said receptacle and normally located above the fuel level to prevent fuel discharge therethrough, said nozzles having tubular extensions inside of said receptacle which communicate with the fuel therein, said nozzles adapted to come successively into operation when the receptacle is rotated from normal position, each nozzle operating at a certain angular position of the receptacle, and each of said nozzles having the communication of its tubular extension with the fuel interrupted when the receptacle is rotated beyond said angular position.

6. In a device of the character described, the combination with a rotatable fuel receptacle, means for maintaining the fuel therein at a predetermined level, and a plurality of fuel discharge nozzles disposed in the wall of said receptacle and normally located above the fuel level to prevent fuel discharge therethrough, said nozzles having

tubular extensions inside of said receptacle which communicate with the fuel therein, said nozzles adapted to come successively into operation when the receptacle is rotated from normal position, each nozzle operating at a certain angular position of the receptacle, and each of said nozzles having the communication of its tubular extension with the fuel interrupted when the receptacle is rotated beyond said angular position.

7. In a device of the character described, the combination with a rotatable fuel receptacle, means for maintaining the fuel therein at a predetermined level, and a plurality of fuel discharge nozzles disposed in the wall of said receptacle and normally located above the fuel level to prevent fuel discharge therethrough, said nozzles having tubular extensions inside of said receptacle which communicate with the fuel therein, and the free ends of which extend to the opposite side of the pivotal receptacle axis from where the nozzles are located, said free ends terminating at varying distances below the fuel level in suitable proportion to the distances at which their respective nozzles are located above the fuel level when the receptacle is in normal position, said nozzles adapted to come successively into operation when the receptacle is rotated from normal position, each nozzle operating at a certain angular position of the receptacle, the free tube end of each nozzle being elevated above the fuel level when the receptacle is rotated beyond said angular position to prevent further operation of the nozzle.

8. In a device of the character described, the combination with a rotatable fuel receptacle, means for maintaining the fuel therein at a predetermined level, and a plurality of fuel discharge nozzles disposed in the wall of said receptacle and normally located above the fuel level to prevent fuel discharge therethrough, said nozzles having tubular extensions inside of said receptacle which communicate with the fuel therein, and the free ends of which extend to the opposite side of the pivotal receptacle axis from where the nozzles are located, said free ends terminating at varying distances below the fuel level in suitable proportion to the distances at which their respective nozzles are located above the fuel level when the receptacle is in normal position, said nozzles adapted to come successively into operation when the receptacle is rotated from normal position, each nozzle operating at a certain angular position of the receptacle, the free tube end of each nozzle being elevated above the fuel level when the receptacle is rotated beyond said angular position to prevent further operation of the nozzle, and each successive nozzle coming into operation before the preceding nozzle goes out of operation.

9. In a device of the character described, the combination with a rotatable fuel receptacle, means for maintaining the fuel therein at a predetermined level, and a plurality of fuel discharge nozzles disposed in the wall of said receptacle and normally located above the fuel level to prevent fuel discharge therethrough, said nozzles having tubular extensions inside of said receptacle which communicate with the fuel therein, and the free ends of which extend to the opposite side of the pivotal receptacle axis from where the nozzles are located, said free ends terminating at varying distances below the fuel level in suitable proportion to the distances at which their respective nozzles are located above the fuel level when the receptacle is in normal position, said nozzles adapted to come successively into operation when the receptacle is rotated from normal position, each nozzle operating at a certain angular position of the receptacle, the free tube end of each nozzle being elevated above the fuel level when the receptacle is rotated beyond said angular position to prevent further operation of the nozzle, and each successive nozzle coming into operation before the preceding nozzle goes out of operation, said receptacle also having a suitable number of nozzles located the highest of all nozzles above the fuel level, which communicate directly with the interior of the receptacle permitting discharge of fuel therethrough when the receptacle is rotated into its extreme angular position. 50 55
10. In a device of the character described, the combination with a rotatable fuel receptacle of a plurality of means for discharging fuel therefrom and means for throwing said discharging means progressively into operation and for progressively disconnecting the inner ends from the fuel to progressively throw the discharging means out of operation, when the mouth of the discharging means is located below the fuel level. 60 65
11. In a device of the character described, the combination with a rotatable fuel receptacle, means for maintaining the fuel therein at a predetermined level, and a plurality of fuel discharge means disposed in the wall of said receptacle having their outer ends normally disposed above the fuel level and their inner ends communicating with the fuel, said discharging means being adapted to come successively and gradually into operation when the receptacle is rotated from normal position, each means operating at a certain angular position of the receptacle and each of said means having the communication of its inner end with the fuel interrupted when the receptacle is rotated beyond said angular position. 70 75
12. In a device of the character described, the combination with a rotatable fuel receptacle, means for maintaining the fuel therein at a predetermined level, and a plurality of fuel discharge means disposed in the wall of said receptacle having their outer ends normally disposed above the fuel level and their inner ends communicating with the fuel, said discharging means being adapted to come successively and gradually into operation when the receptacle is rotated from normal position, each means operating at a certain angular position of the receptacle and each of said means having the communication of its inner end with the fuel interrupted when the receptacle is rotated beyond said angular position. 80 85
13. In a device of the character described, the combination with a rotatable fuel receptacle, means for maintaining the fuel therein at a predetermined level, and a plurality of fuel discharge nozzles disposed in the wall of said receptacle and normally located above the fuel level to prevent fuel discharge therethrough, said nozzles having tubular extensions inside of said receptacle which communicate with the fuel therein, said nozzles adapted to come successively and gradually into operation when the receptacle is rotated from normal position, each nozzle operating at a certain angular position of the receptacle, and each of said nozzles having the communication of its tubular extension with the fuel interrupted when the receptacle is rotated beyond said angular position. 90
